UNITED STATES PATENT OFFICE.

JULIUS M. REIS, OF NEW YORK, AND BENJAMIN WELLS GAMMON, OF BROOKLYN, NEW YORK, ASSIGNORS TO G. REIS & BRO. INC., OF NEW YORK, N. Y., A CORPORATION OF NEW YORK.

PRINTING ATTACHMENT FOR SEWING MACHINES.

Application filed August 21, 1923. Serial No. 658,523.

Our invention relates to a printing attachment for sewing machines, or for machines for sewing or cutting and folding, or otherwise manipulating, labels; or, more broadly speaking, to an indicia-marking attachment for apparatus for securing labels or the like to textile or other articles. More particularly, in its preferred form, it relates to label sewing machines in which labels are stitched onto garments or the like and which machines are provided by our invention with devices for printing or otherwise marking desired indicia, such as the lot number, or size, or other descriptive matter, at desired points on the labels, while the latter are operatively positioned with respect to the sewing mechanism, or, in some cases, the marking devices may be mounted on or attached to a machine which cuts and folds the labels. Labels to be attached to garments may be fed either by hand or automatically into operative relation to a needle which may be caused to sew upon one or more sides, as for example, around the four sides, of the label to secure the same to a garment. The labels when thus presented to the needle carry thereon the manufacturer's name or other data which has previously been printed or woven upon the label. It is often desired, however, to print or mark certain designating data, which may vary from time to time, such as the manufacturer's lot number, or the size, or the name of a retailer, etc., upon the previously printed or woven labels. This has heretofore been accomplished with considerable expenditure of time and labor by subjecting the labels to a separate hand operation, to mark the various lot numbers or the like upon the same without any relation to the sewing or other operations performed upon the labels. Our invention aims to provide an attachment for the sewing or label securing apparatus, or apparatus for otherwise manipulating the label, whereby such indicia may be printed or otherwise marked upon the label in a simple and effective manner, while the label is operatively positioned with respect to the sewing or other label manipulating devices of the machine, whereby considerable time and labor will be saved.

An object of our invention comprises the provision of improved and effective devices of the character referred to. Other objects

of the invention comprise the provision of improved combinations of parts and details of construction, all as will be more fully set forth in the following specification.

In order that the invention may be more clearly understood attention is hereby directed to the accompanying drawings forming part of this application, and illustrating one embodiment of the invention. In the drawings—

Fig. 1 represents a partial front elevation of a label sewing machine equipped with our invention, certain parts being shown in section;

Fig. 2 is a side elevation of the same, certain parts being shown in section;

Fig. 3 is a vertical section taken on line 3—3 of Fig. 1, and

Figs. 4 and 5 are horizontal sections taken respectively on line 4—4 and 5—5 of Fig. 1.

Referring to the drawings, a sewing machine is partially represented, having a head 1 in which a needle 2 is mounted for vertical reciprocation. A garment or other article on which a label is to be stitched is placed on the plate 3 beneath the needle and the label is positioned against the garment in proper position to be sewed along its edges to the garment.

In the machine which is partially illustrated by way of example, a presser foot, indicated generally by the reference character 4, bears upon the garment and upon the label positioned thereon. The member referred to as a presser foot comprises a frame 5, rectangular in form, having a serrated lower edge 6, which is adapted to bear upon the four outside edge portions of the label, with the needle closely adjacent to the inner surface of one of the sides of the frame 5. When the machine is operated the plates 3 and presser foot 4 will be given a suitable feed, by well known mechanism, which need not be illustrated herein, to cause such a relative horizontal movement between the needle and plate 3 and presser foot 4 as to cause the needle to stitch along the outside edges of the label within the four sides of frame 5.

In the apparatus particularly described, when a label is to be positioned in operative relation to the needle, it is dropped into a chute 7 overlying the plate 3 and adjacent to presser foot 4. A label is indicated at 8 within this chute (see Fig. 2), in position to

be fed to the needle. The chute 7 is part of a fixed frame member indicated at 9. The label is adapted to be fed rearwardly, i. e., towards the needle, when the presser foot 4 is raised, by means of a pair of fingers 10 which operate in slots 11 in the bottom of the chute 7. The fingers 10 extend downwardly from a member 12 which is slidably mounted on the fixed member 9 and is adapted to be moved rearwardly, to move the label into the position in which it is to be stitched, by a spring 13, the rear end of which is secured to a suitable point on the fixed frame of the machine, (not shown). Spring 13 is secured at its front end to a trip arm 14 which is pivotally mounted, as is indicated at 15, on the sliding member 12. Pivoted member 14 is provided with a latch shoulder 16 which normally engages an edge of the fixed cover member 9¹ of the chute to hold fingers 10 in their inoperative position.

When a label has been positioned in the chute 7 a foot treadle is operated which serves by suitable mechanism to raise the presser foot 4 and also to swing the arm 14 about its pivot sufficiently to release latching shoulder 16 from its abutment on member 9. Arm 14 is thus swung by means operating upon the arm 17, indicated in Fig. 2 as extending rearwardly from the arm 14. Fingers 10 then operate to push the label exactly under the frame 5 of the presser foot, the rearward movement of fingers 10 being stopped at the proper point by a suitable stop. The presser foot then drops back on the label to cause its serrated lower edge 6 to press the outside edge of the label firmly against the garment resting upon plate 3. We have not deemed it essential to illustrate further the connections by which the presser foot is raised and lowered and latch 16 tripped since the same are well known and constitute in themselves no part of our invention. When the label has been positioned, as described, member 12 and the arm 14 may be again drawn forwardly by means of handle 18 into the position shown in Fig. 2, in which member 14 is again latched and in position to operate upon the next label.

By our invention, in the form disclosed, we provide means for printing or otherwise marking the lot number or other desired designation upon a desired portion of the label as the latter is positioned beneath the presser foot. Accordingly, we provide a reciprocable member which is adapted to descend within the frame 5 of the presser foot to bear at a suitable point upon the label.

In the form of our invention shown in the drawings we have provided a vertical frame 19 which is secured upon the front of the head 1 of the sewing machine. This frame is provided with a suitable vertical slideway in which is mounted for vertical

reciprocation a bar 20, the upper end portion of which, 20^a, extends above frame 19 and is provided with a head 21 for manual operation. The vertically reciprocable member is spring pressed into its upper or inoperative position by means of a spiral spring 22, the upper end of which is secured to the fixed frame, as indicated at 23, while the lower end is secured to a screw 24 mounted on the sliding member 20. 70

Preferably the frame member 19 is provided with a front plate 25 which is secured to member 19 of the frame by screws 26, or the like. This front plate 25 is provided with a vertical slot 27 in which the screw 24 is slidably mounted and in which the spring 22 may be at least partially contained. The sliding bar 20 is preferably provided with an offset rearward extension 20¹, secured thereto or integral therewith, as indicated in Fig. 4, so that the sliding bar and its slideway will in effect form a mortice and tenon joint. The frame 19 and parts carried thereby are shown as secured in position on head 1 of the sewing machine by means of a screw 28 extending through a suitable opening at the upper part of frame 19 and into head 1 of the machine, and a screw 29 which extends through an open ended slot, indicated at 30 in Fig. 1, at the lower left hand corner of frame 19, and into the front of the machine. 75

When access is desired to the needle 2 of the sewing machine for replacement of the same, etc., this may readily be accomplished by loosening screw 29 whereupon the frame 19 and parts carried thereby may be swung to the right, referring to Fig. 1, about the upper screw 28, as a pivot, so as to give free access to the needle 2. 90

The vertically sliding bar 20 carries at its lower end a frame comprising a transverse top portion 31 and vertical side portions 32, 32, which latter are connected by a rear plate portion 33, these parts being shown as integral with bar 20. A type slug 34 is adapted to be positioned within the frame thus formed, a forwardly extending transverse bar 35 being shown, Fig. 3, as secured upon the rear plate 33 to fit into a recess formed on the rear of the type slug. The type slug is held in place by a removable plate 36 which extends down over the type slug and is shown as secured to the slidable bar 20 by means of a screw 37 which extends through a slot 38 formed at the upper end of the plate 36, this slot being open at its upper end so that plate 36 may be removed when the screw 37 is loosened. The lower end of the face plate 25 of frame 19 is cut away, as is indicated at 39, to make room for the upper bifurcated end of plate 36. 100

The type holding frame is completed by a U-shaped member having upwardly extending vertical arms 40, 40, on the outer 105

sides of the arms 32, the arms 40 being connected at the bottom by a transverse portion 41 which extends across the opening below the bottom ends of arms 32. This bottom portion 41 is provided with a longitudinally extending slot 42, through which the face of the type slug may be pressed to bear against the upper surface of the label. Arms 40 of the U-shaped frame are secured to the arms 32 of the inverted U-shaped frame by means of screws 43, which extend into arms 32 through openings in arms 40, which openings are somewhat elongated in the lengthwise direction of the arms, as is indicated for example at 44 in Fig. 1, so as to permit a slight vertical relative movement between the inverted U-shaped frame having arms 32 and the U-shaped frame having arms 40 and transverse bottom portion 41.

Suitable means are provided for properly inking the face of the type member 34 so that the same will properly print upon the label each time it is actuated. This may suitably take the form of a typewriter ribbon 45, which extends beneath the bottom portion 41 of the U-shaped frame. This may be wrapped on a spool 46 supported between ears 47 formed integral with the upper end of the lefthand arm 40, referring to Fig. 1, and extending laterally therefrom. The ribbon may be wound onto the spool 47 supported between ears 48 formed integral with the righthand arm 40 and extending laterally therefrom. Spools 46 and 47 may be provided with knurled knobs 46¹, 47¹, for turning the same. The spool 47 may also be provided with a ratchet wheel 49 which is adapted to be advanced one tooth each time the type bar rises after being depressed by handle 20, the ratchet being thus rotated by means of a spring finger 50 secured by suitable screws 51 to the side of frame member 19.

With this construction, or any other suitable ribbon feeding device, the typewriter ribbon or inking will be moved a short distance after each actuation of the printing attachment so as to present fresh portions of the ribbon to the type. When the ribbon has all been fed from spool 46 to spool 47 it may be replaced or wound back onto spool 46 by hand. Backward movement of ratchet wheel 49 may be prevented by a spring 52 which is wrapped around the upper righthand one of the screws 43, referring to Figs. 1 and 2, this spring being provided with an end portion extending forwardly adjacent to the tooth of the ratchet and bearing upon the forward ear 48. This spring will also serve to depress the U-shaped frame comprising arms 40 and bottom portion 41 relatively to the inverted U-shaped frame comprising side arms 32, this spring preferably having one end portion bearing downwardly upon one of the ears

48 and the other end portion bearing downwardly upon the other ear 48, as is shown in Fig. 5.

With this construction, when a label has been positioned within the frame 5 of the presser foot 4 of the sewing machine, head 21 of the printing attachment is pushed down by hand, resulting in the type bearing frame extending into the frame 5 of the presser foot until the type ribbon is pressed by the bottom bar 41 of the frame against the label. A slight additional downward movement of handle 21 results in a slight further downward movement of the inner or inverted U-shaped frame member carrying the type bar 34, so that the type bearing face of the latter is pressed firmly against the typewriter ribbon to make the desired impression upon the label.

It will be noted that the type bar 34 may be positioned at any desired point in the width of the frame 31, 32, or that several type bars may be mounted in the frame. Accordingly, the lot number, or size, etc., may be impressed on the label adjacent one end of the same and some other desired designation may be printed at another point on the label in alignment therewith; or the position on the label at which the lot number or other indication is impressed may be varied. The plane of movement of the type carrying frame is, however, always so located as to always impress the desired data upon a desired portion of the label, below or away from the manufacturer's name or other printed or woven indication which is carried by the label when the same is placed in position to be sewed or otherwise secured upon the garment or other article which is to bear the same, or when the label is placed in position, generally speaking, to be manipulated or acted upon by mechanism other than the stamping or marking mechanism.

It should be understood that the invention is not strictly limited to the exact details of construction which have particularly been described, but that the same is as broad as is indicated by the accompanying claims.

What we claim is:

1. In a sewing machine, the combination of a frame, devices for sewing labels to articles, carried thereby, means for holding the label firmly on the article in position to be stitched thereto, and means also carried by the frame for stamping desired indicia on labels so held at desired points on the label in spaced relation to the line of stitching.

2. In a sewing machine, the combination of a support, a presser foot for holding a label on an article to which it is to be stitched, a frame, a reciprocating needle carried thereby for stitching the label to

the article, and means also carried by said frame for marking a desired character on the label while the latter is held by said presser foot.

5. In a sewing machine, the combination of a support, a presser foot for holding a label on an article to which it is to be stitched, a frame, a reciprocating needle carried thereby for stitching the label to the article, said presser foot having an opening therein through which the needle operates to stitch around the edge of the label, means for positioning labels accurately beneath said opening in the presser foot, and means also carried by said frame, operable through said opening, for marking a desired character on the label while the latter is so positioned beneath said opening.
10. In a sewing machine, the combination of a support, a presser foot for holding a label on an article to which it is to be stitched, a frame, a reciprocating needle
15. In a sewing machine, the combination of a support, a presser foot for holding a label on an article to which it is to be stitched, a frame, a reciprocating needle

carried thereby for stitching the label to the article, means for feeding labels to position beneath the presser foot, accurately 25 aligned with respect to the needle, and vertically reciprocable means also carried by said frame for marking a desired character on a desired point on the label while the latter is held by the presser foot.

30. In a sewing machine, the combination of a head, a reciprocable needle carried thereby, a frame comprising a slideway secured to said head in front of said needle, and a reciprocable marking device mounted 35 in said slideway, said frame being so mounted on said head as to permit the same to be swung into non-obstructing position with respect to said needle.

In testimony whereof we have signed our 40 names to this specification.

JULIUS M. REIS.
BENJAMIN WELLS GAMMON.
